UNITED STATES PATENT OFFICE.

WILLIAM O. BECK, OF RIDGEFIELD, NEW JERSEY, ASSIGNOR TO WESTERN ELECTRIC COMPANY, OF NEW YORK, N. Y., A CORPORATION OF ILLINOIS.

COIN-RECEPTACLE.

1,121,063.

Specification of Letters Patent. Patented Dec. 15, 1914.

Application filed August 28, 1913. Serial No. 787,131.

To all whom it may concern:

Be it known that I, WILLIAM O. BECK, a citizen of the United States, residing at Ridgefield, in the county of Bergen and 5 State of New Jersey, have invented a certain new and useful Improvement in Coin-Receptacles, of which the following is a full, clear, concise, and exact description.

This invention relates to coin receptacles 10 and more particularly to self-locking detachable cash boxes and appurtenances particularly adapted for use in telephone coin collectors, although obviously not limited to such use.

15 The principal object of this invention is to provide a coin receptacle of the above character which is simple in construction, positive in operation and not easily defrauded.

20 To the above end a novel form of manually set self-locking cash box is provided, which co-operates with the inclosing casing in such a manner that, upon being placed in position, the closure for the coin receiving 25 opening must be locked over the opening before the cash box can be again withdrawn.

The above and other objects of this invention will be fully set forth in the following 30 description and claims, and will be more readily understood by reference to the accompanying drawing in which—

Figure 1 is a plan of the cash box cover, part of the upper wall being broken away, to show the position of the various elements 35 when the box is within its inclosing casing; Fig. 2 is a plan view of the cover with the entire upper wall removed, showing the elements in the position assumed when the cash box is locked upon removal from its inclosed 40 casing; and Fig. 3 is a perspective view of the cash box in position, the inclosing casing being partly broken away.

The cash box 10, when in position, rests within an outer inclosing casing 11 and 45 beneath a coin distributing mechanism 12. The coins descend a chute 13 to the distributing mechanism 12 where they are held to be later delivered to the cash box 10 or a return chute 14 having an outlet in the inclosing casing 11. This coin distributing 50 mechanism may be of any of the forms well known in the art.

The cash box 10 is equipped with a cover 55 20 which is provided with a coin receiving opening 21 through which the coins de-

posited from the distributing mechanism 12 pass on their way to the cash box. Cover 20 may be swung about on hinges located on the back thereof and not shown in the drawings, in order to open up the cash box 60 for the removal of the coins. It is, however, normally held in place by the interlocking of a tongue 24 carried thereby and a lug 22 which is secured to the body of the cash box 10. A seal 23 or any suitable lock may 65 be employed to prevent unauthorized persons from opening the cash box after it has been removed from the inclosing casing.

Within the cover 20 is located mechanism for closing the coin receiving opening 21. 70 This mechanism comprises a pivoted closure 25 adapted to rotate about a pivot 26 and subjected to the tension of a spring 27. The spring 27 is held at one end by a pin 28 and at the other end engages a notch 29 in the closure 25, and tends to force the closure 25 before the coin receiving opening 21 as shown in Fig. 2. The spring 27 serves the purpose of insuring the closing of the opening 21 when the cash box is not in service 80 and thus prevents foreign substances from entering the cash box. It is not essential to the operation of the mechanism and may be omitted. When the closure 25 is over the opening 21, it may be locked in this position 85 by a pivoted or holding member 35. The holding member 35 is pivoted at 36 and is under the tension of a spring 37 which tends to rotate it about the pivot 36 in the direction of the arrow shown in Fig. 2. The holding member 35 may be manually retracted from the position shown in Fig. 2 to the position shown in the dotted lines of Fig. 1, by a key or other suitable means which is adapted to engage a key slot 38 therein, 95 accessible only from the under side of the cover or when the cover is elevated. Excessive retraction of the holding member 35 is prevented by a stop 39. In its retracted position the holding member 100 35 is held by a pivoted member or pawl 40. The pawl 40 is pivoted at 41 and is limited in its movement by a pin 42 engaging the edges of a slot 43 therein. The pawl 40 is under the tension of a spring 105 44 which tends to move the pawl 40 into the position shown in Fig. 2. When the holding member 35 is manually retracted against the pressure of its spring 37, the free end thereof will engage the surface 45 of the 110

pawl 40, thereby retracting the pawl 40 against the pressure of its spring 44. After the free end of the holding member 35 has passed the surface 45, the spring 44 will 5 again advance the pawl 40 until a hooked portion 46 thereof engages the end of the holding member 35, as shown by the dotted lines of Fig. 1. The holding member 35 is thereupon held retracted or in unlocking 10 position until released, as hereinafter described.

The pivoted closure 25 is provided with a portion 50 which extends upwardly from the inside of the cover 20 to the outside 15 thereof through a slot 51, and then laterally beyond the edge of the cover 20, as clearly indicated in Figs. 1 and 2. Integral with or attached to the inclosing casing 11 is a retaining member 52 which through engagement with the cover 20 holds the cash box 10 within the casing 11. At one side the retaining member 52 is provided with an opening 53 through which the portion 50 may extend. The opening 53 is partially closed by 20 a laterally extending pocket 54 of the retaining member 52. The rear edge 55 of the pocket 54 is adapted to engage the portion 50 when the cash box 10 is being withdrawn from the retaining member 52, to rotate the 25 closure 25 to a position before the opening 21. The pivoted closure 25 is likewise provided with a projection 60 adapted, when the closure 25 is rotated about its pivot 26, to be withdrawn from before the coin receiving 30 opening 21, to engage the surface 45 of the pawl 40. Further turning of the closure 25 rotates the pawl 40 about its pivot 41 until the hook 46 thereon releases the holding member 35, which thereupon advances to a 35 position against the projection 61 of the closure 25 as shown by the full lines of Fig. 1. This prevents a sudden withdrawal of the box 10 from the retaining member 52 resulting in the holding member 35 being held 40 in unlocking position by the pawl 40, while at the same time the opening is closed by the closure 25. If now closure 25 is returned 45 so as to cover the opening 21, the holding member 35, due to the pressure of its spring 50 55 37, will follow the closure 25 and when the opening 21 is completely covered will assume an approximately perpendicular position relative thereto, resting against the stop 62 carried thereby. The closure 25 is thereupon 60 locked before the coin receiving opening 21 until the holding member is manually retracted as hereinbefore described.

The construction and adjustment of the various elements are such that when the cash 65 box 10 is inserted into the casing 11 through the appropriate opening, the portion 50 of the pivoted closure 25 projects through the opening 53 and passes inside of the pocket 54. The projection 50 thereupon engages 70 the rear edge of the opening 53 and as the

cash box is forced back into place in the direction shown by the arrows in Fig. 2, the closure 25 is removed from before the opening 21. Lugs 65 carried by the casing door 66 are adapted to engage the cash box 10. 75 These lugs 65 are of such a length that the door 66 cannot be completely closed until the cash box 10 has been moved within the casing 11 a sufficient distance to cause the projection 60 on the closure 25 to engage 75 the pawl 40 and unlock the holding member 35, as shown by the full lines of Fig. 1 and as hereinbefore explained. The cash box cannot now be withdrawn without the complete closing of the opening 21 by the closure 80 25 and the locking of the closure in this position. The portion 50 of the closure 25 and the pocket 54 are so proportioned that the portion 50 projects too far through the opening 53 to allow the cash box 10 to be removed 85 from the retaining member 52 unless the closure 25 has been moved to a position such that the holding member 35 assumes a perpendicular position relative thereto as shown in Fig. 2. This insures the positive locking 90 of the closure 25 in front of the opening 21 before the cash box 10 can be removed. After being removed the cash box 10 may be opened by an authorized person breaking the seal or lock 23, after which the mechanism is manually set for reinsertion into the inclosing casing as hereinbefore described.

In order to prevent the mechanism from being defrauded by means of a string fastened to the holding member 35 and passing 100 through the slot 51, a sharp edged pointed projection 70 is carried by the closure 25. This projection 70 moves past a lug 71 upturned from the bottom wall of the cover 20 and with which it forms shears. A string 105 or small wire which is secured to the holding member 35 to withdraw it from locking relation to the closure 25 will be forced between the sharp edge of the projection 70 and the lug 71 and cut off before the cash box can be inserted far enough to close the door 66. A wire which can resist this cutting action will prevent the complete insertion of the box, since it will arrest the turning of the closure 25.

What I claim is:

1. A coin receptacle comprising a box, a cover for said box having a coin receiving opening therein, a closure therefor, a holding member for locking said closure in closed position, and means for retaining said holding member in unlocking position, said means being controlled by said closure.

2. A coin receptacle comprising a box, a cover therefor having a coin receiving opening therein, a pivoted closure therefor, a holding member for locking said closure in closed position, and means for retaining said holding member in unlocking position,

said means being controlled by said closure.

3. A coin receptacle comprising a box, a cover therefor having a coin receiving opening therein, a pivoted closure therefor, a manually retracted holding member for locking said closure in closed position, a pivoted member for retaining said holding member after being 10 manually retracted, and means carried by said closure for engaging said pivoted member to cause the release of said holding member.

4. In a device of the character described, 15 the combination of a coin box, an inclosing casing therefor, a cover for said box having a coin receiving opening therein, a closure therefor, a holding member for locking said closure, and means for retaining 20 said holding member in unlocking position, said closure and casing coöperating to remove said closure from in front of the opening and controlling said means to release said holding member.

25 5. In a device of the character described, the combination of a cash box, a retaining member therefor, a cover for said cash box having a coin receiving opening therein, a pivoted closure for said coin receiving 30 opening, a holding member for locking said closure before the coin receiving opening, a pawl for retaining said holding member in unlocking position, and means carried by said closure and coöperating with said 35 retaining member for moving said closure to open position, controlling the return movement thereof, and releasing said holding member from said pawl.

6. In a device of the character described, 40 the combination of a retaining member provided with an opening therein, a cash box, a cover therefor having a coin

receiving opening therein, a pivoted closure therefor, a spring tensioned manually retracted holding member for locking 45 said closure before the coin receiving opening, a spring tensioned pawl for retaining said holding member in unlocking position after said holding member has been manually retracted, and projections on said closure coöperating with the edges of the opening in said retaining member, said pawl and said holding member, to remove the closure from before the coin receiving opening upon the insertion 50 of said cash box into said retaining member, release the holding member from said pawl and insure the closing of the coin receiving opening and the locking of said closure by said holding member before said 55 cash box can be completely removed from said retaining member.

7. A coin receptacle comprising a box, a cover therefor having a coin receiving opening therein, a closure therefor, and means 60 secured to said cover and coöperating with said closure to form cutting shears.

8. A coin receptacle comprising a retaining member, a box which can be inserted therein, a cover for said box having a coin 65 receiving opening therein, a pivoted closure therefor coöperating with said retaining member, and means coöperating with said closure to form shears to cut off an obstruction therebetween or prevent the 70 complete insertion of said box into said retaining member.

In witness whereof, I hereunto subscribe my name this 25th day of August A. D., 1913.

WILLIAM O. BECK.
